METHOD AND MEANS FOR VENTILATING THEATERS AND DISTRIBUTING SOUND

Application filed August 5, 1929. Serial No. 383,592.

This invention relates to methods and means for ventilating theaters and distributing sound and has a special application to theaters in which motion pictures are displayed with a synchronized sound accompaniment.

An object of the invention is to discharge a current of air from a region adjacent to the stage of a theater auditorium to the rear of such auditorium in such volume and direction as to appreciably assist transmission to the audience of sounds emanating from the stage.

More specifically, the invention seeks to assist in carrying sound waves from a motion picture screen (through which said waves are thrown by a suitable loud speaker or the like) to all parts of a theater or auditorium without undue distortion or diminution thereof.

These and various other objects the invention attains by the construction hereinafter described and illustrated in the accompanying drawings, wherein:

Fig. 1 is a perspective interior view of a motion picture theater, showing a preferred location for the opening into said theater of a ventilation system.

Fig. 2 is a diagrammatic longitudinal sectional elevation of said theater, showing a provision for delivering air in a certain advantageous relation to the screen on which the pictures are thrown.

Fig. 3 is a horizontal sectional view of the frame through which air enters the theater, disclosing air-directing louvers carried thereby.

Fig. 4 is a vertical sectional view of the same.

Fig. 5 is a cross-sectional view of a fragmentary portion of the screen showing its perforated construction.

Fig. 6 is a fragmentary front view of the same.

In these views, the reference character 1 designates the stage of a theater and 2 the usual proscenium arch, framing the front of the stage. Upon (or above) said stage, and preferably in a central location is a motion picture screen 3. To permit sounds to ap-

parently emanate from said screen it is formed with minute perforations 4 and a loud speaker 5 of any suitable construction is arranged at the small end of a sound box 6, connected with the back of said screen and progressively reduced in cross section as it extends to said speaker.

The described arrangement of screen and loud speaker is at present widely used in connection with synchronized sound-producing and picture displaying apparatus, and a more detailed explanation of same would hence be superfluous. The sound waves leaving said screen are primarily directed toward the rear of the theater, but with such lateral divergence as to reach the side sections and central section in substantially the same volume.

The present invention proposes to discharge a considerable current of air at low velocity in substantially the direction of travel of said sound waves, thereby counter-acting to a quite appreciable extent the tendency of said waves to diminish in force and clarity as they advance. Thus there is provided, adjacent to the stage and preferably centrally thereabove, an air outlet fitting 7, which preferably is positioned just in front of the central portion of the arch 2. Said fitting may have any desired contour and may conveniently have the elongated rectangular form, best illustrated in Fig. 1. Leading to and discharging from said fitting is an air duct 8, through which a large volume of air may be impelled at low pressure by a blower 9. The latter may have any desired location and may be conveniently situated upon the theater roof 10.

Provision is made for the venting of air at the rear of the theater by extending one or more ducts 11 from the ceiling of the theater through the roof thereof.

In Fig. 2 the lines 12 indicate the expanding path of the rearwardly traveling sound waves and the intersection of said path by the ventilating flow of air is indicated by arrows.

It has been found that in installing a ventilating system in the described relation to a screen and sound apparatus that the sound waves are more fully distributed throughout

a theater in effective volume and that distortion effects are materially lessened. The improved sound distribution is, it is believed, largely due to the effect of the above-described ventilation system in increasing the density of that portion of the air in the theater through which the sound waves travel to the audience.

In thus utilizing a ventilating current of air to augment travel of sound waves, it is desirable to locate the air outlet fitting sufficiently remote from the seats that the air current may largely lose its initial velocity before reaching the audience, whereby the existence of said current will not be unpleasantly perceptible. Also it is desirable to secure, so far as is practicable, a coincidence of direction between said air current and the advancing sound waves. The location of the discharge fitting 7 close adjacent to the central top portion of the arch 2 peculiarly permits the desired expansion of the air current prior to its encountering the audience and a low angularity of direction between said current and the sound waves. In Fig. 2, it best appears how the fitting 7 is inclined to impart the desired direction of travel to the air current.

As a further provision for controlling the direction and expansion of the air current to meet various conditions, sets of relatively transverse pivotal louvers 13 and 14 may be mounted in the fitting 7, extending respectively horizontally across the opening thereof and parallel to the side edges of said opening. Said louvers may be set at such differential angles as will secure most effective augmentation of the sound waves by the discharging air.

While a single air outlet fitting adjacent to the arch 2 has been illustrated, it is to be understood that a plurality of such fittings might in some cases be employed and that the invention is susceptible of various other modifications.

What I claim is:

1. The method of utilizing a ventilating current of air to improve sound distribution, consisting in directing sound waves from a stage toward the rear of a theater, and discharging a ventilating current of air from a region adjacent to the stage and overlying the path of the sound waves in a rearward direction and at a downward inclination and in such volume as to materially increase the density of the air through which said sound waves travel to the audience, and venting such air at the rear upper portion of the theater.

60 2. A method of employing a ventilating current of air to improve sound distribution, consisting in generating sound waves adjacent to one end of an auditorium and directing such waves toward the other end of the 65 auditorium, discharging a ventilating cur-

rent of air at a point adjacent to the source of said waves but outside of their path, and directing said air current in the general direction of said waves and convergently to their path and venting such air from the rear upper portion of the auditorium whereby the travel of the air and sound waves are substantially conformed throughout the major portion of their travel, the volume of the air so discharged being adequate to materially increase the density of the air body in the lower portion of the auditorium through which body said sound waves are transmitted to the audience.

3. The combination with a theater stage and proscenium arch, of a means for directing sound waves from said stage toward the rear of the theater, means for conducting air into the theater and discharging it at a point above the path of said waves and adjacent to the top of said arch and for directing such air rearwardly at a downward inclination in such volume as to materially increase the density of the air through which said sound waves are conveyed to the audience, and means for discharging said air at the rear of the theater.

4. In an apparatus of the character described, the combination with means within an auditorium and adjacent to one end thereof for directing sound waves toward the other end of said auditorium, means for continuously introducing ventilating air into the auditorium through the ceiling thereof at a point adjacent to the source of said waves, said means providing for directing such current convergently to the path of said waves in a volume adequate to materially increase the density of the air body through which said waves are conveyed to the audience, and means for venting such air from the upper portion of said auditorium at the end thereof toward which said waves are directed.

In testimony whereof I sign this specification.

RAY E. VENDERBUSH.
